Albert S. Jackson, Wood River, and Clarence A. Heyne, John R. Johnson, and John E. McLaughlin, Alton, Ill., assignors to Owens-Illinois Glass Company, a corporation of Ohio

Application October 21, 1950, Serial No. 191,472

23 Claims. (Cl. 101—40)

Our invention relates to a method and apparatus for applying lettering and surface decorations to various articles by an offset printing process. The invention is designed for use in applying lettering and other designs and decorations, including single and plural color designs, to the cylindrical surfaces of bottles, jars and various other round articles.

The invention provides an apparatus in which the ink is applied to offset dies and transferred by the dies to a blanket which in turns transfers the printed design or designs to the articles which are being printed. The apparatus is herein illustrated and described as designed and used for printing lettering, decorative designs and the like, on the cylindrical bodies of round glass bottles, although not limited to such use.

Glass bottles and jars as manufactured and in commercial use at the present day, are never perfectly round and usually have slightly sunken or bulged spots or areas on their outer surfaces. In printing such an article it is necessary in order to obtain a satisfactory transfer of the design from the printing blanket to the surface of the article, to have the printing blanket backed up with a yieldable material for distributing the pressure applied through the blanket, thereby forcing it into such low spots or depressions and also causing it to absorb the high spots; otherwise the design will be imperfect and incomplete.

However, such a yieldable backing material does not lend itself to maintaining a kiss touch (that is, a very light touch) of the printing die to the blanket at the point or area of applying the ink to the blanket by means of the offset die. This kiss touch is found to be very necessary for the successful operation of the offset printing process.

The present invention is designed to overcome this difficulty and for this purpose provides different materials to back up the blanket at the point at which the ink is applied thereto and the point of printing the article. More specifically, there is provided a traveling blanket or a plurality of blankets connected end to end for travel in a closed path. The blankets pass over two separate rolls, one of which provides a backing for the blanket at the area where the ink is applied thereto by the die and the other backs up the blanket where the design is transferred from the blanket to the article which is being printed. Where the ink is applied by the offset die to the blanket a non-yieldable roll is used to insure and maintain a kiss touch between the blanket and the die. With this arrangement the only variations encountered will be in the thickness of the blanket itself and this can be controlled so that an excellent kiss touch is assured. At the point where the blanket transfers the ink to the article being printed a back-up roll of comparatively soft yieldable material is provided. The traveling blanket passing over this yieldable roll has the properties necessary for printing the uneven surface of the bottle or other article. The back-up roll is of much smaller diameter than that of the bottle and this makes the roll more reliable and

2

effective for counteracting irregularities in the surface which is being printed, particularly as it permits the roll to enter and follow the contour of depressions in such surface.

5 The invention provides, in combination with the printing mechanism, a bottle carrying apparatus which picks up and orients each bottle, conveys it to the blanket where it receives the print and then discharges it onto a conveyor by which it is transferred to an oven for curing 10 the ink.

The apparatus as herein illustrated is designed for multiple color printing. It provides a number of units each including an offset die, an ink fountain and intermediate rolls for transferring the ink and applying it to the die. 15 The blankets are carried by endless chain carriers in a closed path in which the blankets pass over a rotating blanket drum. The drum provides a backing for the blankets while the latter are receiving the designs from the offset printing rolls which rotate in contact with the 20 blankets. The bottles or other articles to be printed are brought to the printing zone and carried therethrough in a straight path by endless conveyors, with the articles in rolling contact with the blanket.

A back-up roll unit which comprises a series of back-up 25 rolls traveling in a closed path, is positioned behind and adjacent to the path of the blankets through the printing zone so that the blankets pass between the bottles and back-up rolls. The latter travel with the bottles and apply a yielding pressure to the blankets by which the 30 design is transferred to the bottles.

The bottle carrying spindles are spaced at equal intervals and travel continuously at a uniform speed, both the upper and lower spindle conveyors being positively driven and traveling in closed paths. The path of the bottles through the printing zone is in a straight line, the movement of the printing blankets also being in a straight path through the printing zone. The higher speed of the blankets as compared with that of the bottles serves to roll the bottles along the blanket but at a slower speed 35 than that at which the blanket is traveling. This is an important feature particularly in high speed work as it enables a much more satisfactory transfer of the design than is possible with the bottle rolling at a higher speed.

Referring to the accompanying drawings:

Fig. 1 is a plan view of an apparatus embodying our 45 invention, a portion of the article conveying mechanism being broken away.

Fig. 2 is an elevational view of the same.

Figs. 3a, 3b and 3c are sectional elevations at the 50 line 3—3 Fig. 1 and together give a composite view of the machine in sectional elevation. Fig. 3a shows an ink fountain, a die roll, means for transferring the ink to the die roll, the blanket roll and the blanket running between the die roll and blanket roll. Fig. 3b shows a design being transferred from the blanket to a bottle. Fig. 3c is a section through the conveyor mechanism by which the bottles are supported and carried to and through the printing zone.

Fig. 22A is a detail of means for adjusting a die roll.

Figs. 23 to 28 illustrate the back-up roll unit. Fig. 23 is a plan view of the back-up roll unit and also shows a blanket carrier chain. Fig. 24 is a sectional elevation with parts broken away, taken at the section line 24—24 on Fig. 23. Fig. 25 is a part sectional elevation of the back-up roll mechanism. Figs. 26, 27 and 28 are sectional views at the correspondingly designated section lines on Fig. 25.

General arrangement of parts

The general arrangement and cooperation of parts will be understood by reference to Figs. 1, 2 and 5. A plurality of inking units 30 are provided, each comprising an ink fountain 31, an offset die roll 32 to which ink is supplied through intermediate rolls including a leveling roll 33, a fountain roll 34, former rolls 35 and 36 and cutter rolls 37, 38. The offset die roll 32 carries the die with the design which is to be transferred to the bottles.

Blankets 40 are connected end-to-end in a continuous series trained over a blanket drum 41 and rolls 42 and 43. The blankets are attached to endless sprocket chains including an upper chain 44 and a lower chain 45 (Fig. 3b). The chains are trained over sprocket wheels 47 attached to the drum 41, and sprocket wheels 48 and 49 attached to the rolls 42 and 43 respectively. The blanket drum is rotated continuously in a counter-clockwise direction by power supplied to the blanket drum shaft 46.

The workpieces 50, herein shown as bottles, may be brought to the printing apparatus on a horizontal traveling conveyor 51 (Fig. 2) and are uniformly spaced thereon and positioned for registration with the holding chucks by means of a spiral conveying and spacing device 52 (Fig. 5). The bottles while passing through the printing zone are held between the bottom chucks or supporting pads 54 and neck chucks 55. The neck chucks are lowered into engagement with the bottles

while the latter are on the conveyor 51. Suction is applied through each chuck when lowered for vacuumizing and holding the bottle. The chuck is then raised to lift the bottle off the conveyor and is carried forward into register with a bottom pad or chuck 54 and lowered to place the bottle on the pad. The bottle while held between the chuck 55 and the pad, is carried through the printing zone. As the bottles while thus held are brought opposite the traveling blankets 40, each bottle is held in rolling contact with the traveling blanket by means of backing rolls 57 while the design is printed thereon. The backing roll unit comprises a plurality of the rolls 57 connected to endless chain carriers 58 trained over pulleys on a drive shaft 60 and driven shaft 59 as hereinafter described. The backing rolls are advanced at the same speed as the bottles while the blanket passing between a bottle and its backing roll, is traveling at a substantially higher speed so that the bottle and backing roll are rotated about their axes while the design is being transferred to the bottle from the blanket.

Referring to Figs. 7 and 8, the machine is driven by a motor M geared through a belt 62 to a drive shaft 63. The latter has a driving connection with a conveyor drive shaft 64 through a train of gearing including a shaft 65, couplings 66, 67, beveled gears 68, 69, worm shaft 70 and a worm 71 thereon which runs in mesh with a worm wheel 72 keyed to the conveyor drive shaft 64.

The lower bottle conveyor includes endless sprocket chains 73 and 74 (Fig. 2) running on driving sprocket wheels 75 (Fig. 5) on the drive shaft 64 and driven sprocket wheels 76. Vertical spindles 77 attached to the chains 73, 74, as hereinafter described, carry the bottle supporting pads 54. The upper bottle conveyor, positioned directly over and of somewhat greater length than the lower conveyor, includes upper and lower sprocket chains 78 and 79 which are trained over sprocket wheels on the drive shaft 64 and over driven sprocket wheels 81 on a shaft 64'. The bottle carrying in conveyor 51 (Figs. 2 and 8) and the take out conveyor 82 (Fig. 5) to which the bottles are delivered after the printing operation, are driven by the motor M operating through shafts 63 and 83 and driving connections (not shown).

The blanket drum 41 is mounted by means of ball bearings 85 (Figs. 3a and 3b) for rotation on a tubular shaft 86 bolted to a frame member 87 or case which encloses certain gearing. The drum shaft 46 extends vertically through and is journaled within the tubular shaft 86. An annular plate 88 provides the driving connection between the shaft 46 and the drum 41. The shaft 46 is driven from the shaft 70 (Fig. 7) through gearing including a coupling shaft 88^a, worm shaft and worm 88^b, and worm gear 88^c keyed to the shaft 46 (Figs. 6 and 7).

Inking unit

The construction and operation of an inking unit 30 will now be described, such unit including an offset die roll 32 and the means for supplying ink thereto from the fountain 31. The die roll 32 (Fig. 3a) is removably mounted on the upper tapered end of a shaft 90 which is driven from the blanket drum shaft 46 operating through a gear 91 keyed on the shaft 46 and meshing with a gear pinion 92 on the shaft 90. The gear 92 has a slideable connection 93^a (Fig. 3a) with the shaft 90 which permits up-and-down adjusting movement of the shaft for a purpose presently described. The lower end of the shaft 90 is journaled in a bearing sleeve 93 within which is a ring 94 providing a bottom support for the shaft. The bearing 93 has a screw-threaded connection with an adjusting element 95, shown as a worm gear (Fig. 22). The gear 95 is rotatively mounted in an outer cylindrical member 97 which forms an integral part of a casing 98 (Figs. 3a and 6). The case 98 carries the die roll and other rolls of the inking unit and is adjustable toward and from the blanket roll for adjusting the die roll relative to the blanket roll and blankets.

The die roll 32 is adjustable rotatively by a vertical adjustment of the shaft 90 which, owing to the inclination of the intermeshing gear teeth of the gears 91 and 92, imparts a spiral up or down movement to the shaft. Such spiral movement is effected by rotating the gear 95 which is screw-threaded on the shaft supporting bearing 93. The adjusting gear 95 meshes with a worm 99b (Figs. 22 and 6) on a worm shaft geared to a vertical shaft 99a operatively connected through gears 99 (Fig. 22A) to an adjusting knob 100 (Fig. 20).

A non-rotative vertical adjustment of the die roll 32 is effected by adjusting the case 98 vertically. The adjusting means includes a worm gear 102 (Fig. 3a) which has a screw-threaded connection with a tubular member 103, the latter providing a support for the ball bearing cage 104 with the ball bearings on which the shaft 90 is supported. The worm gear 102 is rotated by means of an adjusting knob 105 having operating connections with the worm gear similar to those for operating the lower gear 95. The bearing 93 is held against rotative movement by a guide block 106 bolted to the case 98 and engaging a vertical slot in the member 103. When the knob 105 is rotated, the case 98 and the rolls supported therein are moved up or down. The adjusting knobs 100 and 105 thus serve for adjustment of the die roll both vertically and rotatively, thereby permitting an accurate adjustment of the position at which the design is applied to the blanket.

The leveling roll 33 is mounted on a shaft 108 which is rotated continuously by means of a gear pinion 109 keyed to the shaft and driven by the pinion 92 operating through an idler gear 110 (Fig. 6) running in mesh with the gear pinions 92 and 109. Attached to the lower end of the shaft 108 is a cam 111 surrounding the shaft and having its upper surface in the form of a continuous cam track. The cam serves to impart vertical reciprocating movement to the cutter rolls 37 and 38. The operating connections between the cam and the cutter rolls include a yoke 112 (Figs. 3a and 22) with trunnions by which the yoke is mounted for rocking movement. The yoke carries cam follower rolls 114 which run on the cam track. One of the trunnions has attached thereto a rock arm 115. Vertical rods 116 (Fig. 6) bear at their lower ends on the rocker arm 115 and have their upper ends beneath and in supporting engagement with the shafts of the cutter rolls 37 and 38. A rock arm 117 pivots in a supporting bracket 118 above the cutter rolls and engages the upper ends of the cutter roll shafts and operates through said shafts to hold the rods 116 in contact with the lower rocker 115 so that a positive up-and-down movement is imparted to the rods 116 and the cutter rolls. A yielding pressure of the cutter rolls against the leveling roll 33 is maintained by coil springs 119 adjacent to the upper and lower ends of the rolls. The tension of the springs is adjustable by means of knobs 120.

The inking unit, including the die roll 32, is adjustable toward and from the apron drum for accurately adjusting the position and pressure of the die against the aprons and obtaining the desired light contact pressure or kiss touch of the die as it runs in contact with the apron. For this purpose the casting 98 or case which carries the inking rolls is adjustable bodily toward and from the blanket roll. The position of adjustment is determined by an adjustable stop screw 121 (Fig. 3a) having a screw thread connection with the carrying frame 87 and rotatable by a hand crank 122. The screw 121 is held in adjusted position by a clamp screw 124. A coil spring 125 under compression, operates through a rod 126 to yieldingly hold the case 98 against the stop screw 121. Adjustment of the screw 121 serves to adjust and regulate the pressure of the die against the blanket.

The former rolls 35 and 36 are held in frictional contact with the die roll and the leveling roll 33. Referring to Figs. 20 and 21, each former roll comprises a body 127 of rubber or other suitable material with an inner liner consisting of a tube 128. The roll is

removably mounted for rotation on a shaft 129 which extends downward through a block 131 fitted thereon and cooperating with means by which the roll is adjustable laterally and its pressure against the die roll 32 and leveling roll 33 are regulated as presently described.

The roll 35 is mounted in upper and lower ball bearings 132 for rotation about the shaft 129. The shaft is frictionally held against rotation by means of a compression coil spring 133 mounted on the lower end of the shaft and applying downward pressure by which the lower ball bearing casing is held against the block 131. A hand knob 134 has a tubular shank 135 extending downward within the tube 128 and formed with a bayonet slot 135a which engages a pin 135b on the tube 128. Rotation of the hand knob serves to release the roll and permit it to be lifted from the shaft.

The means for adjusting the former rolls 35, 36 laterally comprises the adjusting blocks 131 (Figs. 20, 21) heretofore mentioned. Each said block is approximately wedge-shaped as shown in dotted lines (Fig. 20) providing bearing surfaces which are convergent in a direction extending outwardly from the center of the block. Referring to Fig. 21, a short shaft 136, journaled in a block 137, has a screw-threaded connection with an adjusting head or member 138 formed with an inclined bearing surface 139 in engagement with the inclined bearing surface of the block 131. A second adjusting head 141 bears against the opposite inclined surface of the block 131.

The stud shaft 136 is rotatable for adjusting the block 131, by means of a worm gear 142 attached to the shaft and running in mesh with a worm 143 on an adjusting rod 144 which, as shown in Fig. 20, is connected through a universal joint 145 to a rod 146 and adjusting knob 147. A coil spring 148 (Fig. 21) held under compression between the bearing blocks 131, holds said blocks outwardly against the adjusting heads 138 and 141. An adjusting knob 150 is operatively connected to the block 141 in the same manner that the knob 147 is connected to block 131, as above described. Such connections include rod 151 and worm gear 152. An adjustment of the former roll 36 for example, toward the die roll is effected by rotating the knob 147 in a direction to retract the adjusting head 138 and then rotating knob 150 in a direction to move the block 141 forwardly thereby forcing the former roll toward the die roll. The former roll 36 is adjustable by means of adjusting knobs 153 and 154 operating through connections identical with those through which the knobs 147 and 150 operate.

A transfer roll 155 interposed between the fountain roll 34 and the leveling roll 33 is mounted for oscillating movement by which the ink is transferred from the fountain roll to the leveling roll. The roll 155 is carried by rock arms 156 on a vertical rock shaft 157 (Figs. 3a, 20 and 22). Means for oscillating the shaft 157 comprises an eccentric 158 formed integral with the cam 111.

A rocker 160 is rotatively mounted on the eccentric 158, and is connected at one end through a link 161 to the casing 97. The opposite end of the rocker 160 is connected by a pivot 162 to one end of a rod 163. The other end of the rod is slidably connected to a rock arm 164 formed on a hub 164a or rocker mounted for rocking movement about the axis of the shaft 165 which carries the inking roll 34. A link 166 (Fig. 22) is pivoted at one end to a rock arm on the rock shaft 157 and has an adjustable slot and pin connection 167 with the rocker 164a. A coil spring 168 mounted on the rod 163 is held under compression and bears against the rock arm 164, thus providing a yielding connection between the rockers 160 and 164.

Rotation of the leveling roll shaft 108 operates through the rocker 160, rod 163, rock arm 164 and link 166, 75 to rock the shaft 157 and oscillate the roll 155 between

the fountain roll and the leveling roll 33. The movement of the roll 155 in a direction toward the leveling roll 33 is limited by a stop screw 170 (Figs. 22 and 6) in the path of the rocker arm 164. The rocker 164^a may be locked in position to hold the roll 155 away from the leveling roll 33. The locking means for this purpose comprises a latch 174 connected by a pivot 175 to a bracket 171 and formed with a hook 176 to engage the rocker 164^a. The latch 174 is held in its inoperative position (shown in dotted lines, Fig. 22) by a cam 177 actuated by a hand lever 178. The spring 168 and slideable connection of the rod 163 with the rock arm 164 permit the latter to be locked as just described without interfering with the continuous rotation of the leveling roll shaft 108.

The rocker 164^a has a one-way driving connection with the inking roll shaft 165 through a one-way clutch 179 (Fig. 3a) so that the eccentric 158 operating through the rod 163 imparts an intermittent step-by-step rotation of the inking roll in one direction.

The printing die 181 (Figs. 3a, 20), in the form of a sheet is wrapped around the die roll 32 and its ends gripped by a pair of clamping bars 183. The sheet is attached to the roll by screws 184. The design 185 (Fig. 6) on the die 181 is transferred to a blanket 40 as shown at 185a.

Blankets

Referring to Figs. 15-19, the blankets 40, made of rubber or like material, are attached to the carrier chains 44 and 45 by the following means:

Each blanket has attached to its ends a pair of bars 186. Each bar may consist of a piece of thin sheet metal bent double with the marginal portion of the blanket 40 clamped therebetween as shown in Fig. 19. One of the bars 186 is connected to the carrier chains through tension devices each of which comprises telescoping or slidably connected members 187 and 188. Member 187 is formed with a bore in which is housed a coil spring 189 held under compression between the members 187 and 188. Member 188 is connected to the carrier chain by a connecting piece 190. The member 187 is provided with a button 191 for attachment to the bar 186, the latter being formed with a buttonhole 193 to engage the button. The bar 186 at the other end of the blanket is connected to the carrier chains by connecting blocks 194 and buttons 192. The blanket is held under a continuous and constant tension by means of the compression springs 189 while the position of the blanket lengthwise of the chain is held constant by its connection with the blocks 194.

Lower conveyor

The lower bottle conveyor (shown in Figs. 2, 3b, 3c, 11-14), is made up of a series of single units each comprising a spindle 77, the spindles being carried by the endless chains 73 and 74 as before mentioned. Referring to Fig. 11, the spindle comprises a vertical tubular spindle shaft 196 connected to the chains 73 and 74 by means of bearing blocks or members 197 and 198. The chain 73 is connected by a pivot pin 199 to the bearing block, the pivot pin being mounted in roller bearings. The spindle is held vertical and guided during its travel by upper and lower guide rails 200 and 201 formed with cam grooves or tracks in which run rolls 209a and 202 mounted on the bearing members 197, 198. The rails 200 and 201 are mounted on a frame 203 (Fig. 3c). The weight of the spindle is carried by an arm 204 formed thereon and carrying a roll 205 running in a groove or track formed in a guide rail 206 on the frame 203 (Figs. 2 and 11).

The bottle supporting pad 54 (Fig. 11) is provided with a depending stem 220 mounted in ball bearings 207, the ball bearing cage being mounted in the upper end of a tubular shaft or member 208, mounted at the upper end of the spindle shaft 196 and forming the upper end portion of the spindle 77. The lower portion of the member 208 is extended downwardly within the spindle shaft. A

shoulder 208^a on the member 208, seats on the spindle shaft 196. The bottle supporting pad 54 is freely rotatable in the ball bearings 207 during a portion of its horizontal travel and during another portion of its travel is frictionally held against free rotation in the operation of rotatively adjusting the bottle thereon as will presently be described.

A means for applying such friction comprises a coil spring 210 mounted in the lower half of the spindle shaft 196. Above the coil spring is a tube 211 also mounted within the spindle shaft. A rod 212 positioned centrally within the shaft 196 is keyed at its lower end to a roller 213 which runs on a track 214 on the frame 203. The roller 213 may be provided with a rubber tread 215 or other means to obtain a good frictional or positive traction. The rod 212 has a driving connection through a connecting head 216 with a rod 217 extending through the upper portion of the spindle 196. A key 216^a connects the rod 212 to the head 216. The upper end of the rod 217 is formed with a head 218 over which is a friction disk 219 fitted on the lower squared end of the stem 220 of the pad 54.

During that portion of a cycle in which the friction drive of the pad 54 is required, the upward pressure of the spring 210 maintains frictional contact between the head 218 and the rotating disk 219. In order to remove the friction and permit the pad to rotate freely in its ball bearings, the tube 211 is lowered a short distance by a cam 221 which operates a bell crank lever 222 having a pivotal connection 223 to the spindle. One arm of the lever 222 is connected to a link 224 which carries a pin 225 extending through a slot 226 in the wall of the tube 211. The link 224 and bell crank 222 provide a toggle connection by which the sleeve or tube 211 is lowered when bell crank 222 is operated. The toggle permits the tube 211 to be held in its lowered position independently of the cam 221. When the tube 211 is lowered, the upper rod 217 is permitted to drop a short distance out of contact with the friction disk 219, thereby breaking the frictional driving connection with the pad 54. Ball bearings 227 at the lower end of the spindle shaft permit free rotation of the rod 212 within the shaft. Ball bearings 228 are provided between the non-rotatable tube 211 and the rotatable head 216.

Orientation of bottles

Hollow glass articles such as bottles and jars are usually blown in split molds which results in producing more or less pronounced vertical seams in the outer surface of the glass at the parting lines of the molds. The present invention provides means for rotatively positioning or orienting the bottles relative to the printing dies, so that the design will be printed at a predetermined position to avoid interference between the design and the seams. The means for thus orienting the bottles will now be described, referring particularly to Figs. 11-14. Each bottle is formed with a small lug 230 near the lower end thereof and in a predetermined position relative to the vertical seam. The member 208 forming the upper end of the spindle shaft has attached thereto a horizontal guide bar 231 on which is slidably mounted a slide bar 232. A stop pin 233, herein referred to as the register finger, is attached to the slide bar at one end thereof. The slide bar is movable into a stop position in which the pin 233 is in the path of the stop lug 230 on the bottle 50. The spindle section 208 is formed with an extension 234 (Fig. 12) to which an arm 235 is bolted. A rocker 236 is journaled in the arm 235 and carries a cam follower roll 237 which runs on stationary cams 238 and 239 (Figs. 11, 12 and 14). The rocker 236 is formed with an arm 240 which serves as a latch to engage the slide bar 232 as shown in the lower part of Fig. 12, and thereby hold the register finger 233 in its retracted position. When the cam roll 237 runs up the cam 238 the arm 240 is swung away from the slide bar 232, permitting the latter to be

drawn toward the bottle by a coil spring 241 attached to the slide bar, thereby moving the stop pin into contact with the bottle and in the path of the stop lug 230. At this time the pad 54 is being rotated by the friction drive disk 219 so that the bottle thereon will be rotated until arrested by engagement of the stop lug 230 with the stop pin 233. The rotative movement of the rocker 236 is limited in both directions by a stop pin 242 thereon and lugs 243 and 244 on the arm 235. The cam 239, Fig. 14, rotates the rocker 236 in a counterclockwise direction so that the slide bar 232 is operated in a direction to withdraw the finger 233, leaving the bottle free for rotation.

The upper spindle section 208 is connected to the spindle shaft 196 by means of arms 246 and 246' (Figs. 12, 13) extending laterally from said parts and secured together by a pin 248. Relative rotation of the parts 208 and 196 is thereby prevented. The rotative position and movements of the spindle about its vertical axis are controlled through the upper and lower bearing members 197 and 198. The upper member 197 is formed with a horizontal arm 247 (Figs. 2 and 14). The roll 200^a and a roll 200^b at the opposite ends of the arm 247 run in the channel 249 or track, formed in the guide rail 200.

The track comprises straight portions and arc-shaped portions 250 concentric with the drive shaft 64, and driven shaft of the conveyor. The lower bearings 198 are also provided with forwardly extending arms 251 (Fig. 2) substantially similar to the upper arms 247 and provided with rolls running in the lower track 201. It will be observed that the guide rolls at the forward ends of the arms 247 and 251 reach the curved section 250 of the tracks in advance of the spindles so that the rotative movement of each spindle about its axis is commenced before the spindle reaches the arc in which it travels about the axis of the driving shaft. This arrangement is conducive to a smooth operation avoiding the tendency to a sudden or jerky movement of the spindle as it commences its travel in the arc-shaped path. The same smooth action is obtained as the spindle leaves the curved portion of its path.

Upper conveyor

The upper conveyor mechanism (shown in Figs. 1, 2, 3b, 4, 9 and 10) comprises a series of spindle units each including a neck chuck 55 to seat on the bottle neck and a spindle 253 carrying the chuck. The conveyor mechanism, including the spindles 253 and the upper and lower sprocket chains 78, 79 is supported directly over the lower conveyor, being mounted on a structure comprising a tank 254 (Fig. 4). The tank provides a vacuum chamber 255 in communication with the chucks 55 through suction lines as hereinafter described for vacuumizing the bottles and holding them to the chucks by suction during the printing operation.

The tank 254 is suspended from an overhead horizontal beam 256 (Figs. 2 and 4) mounted on posts 257 and 258 at the ends of the tank. The beam 256 is of U shape in cross section (Fig. 4). The tank is suspended from the beam 256 by a pair of rods 259 attached to the upper wall of the tank and screw-threaded through worm gears 260 supported on the beam 256. Means for rotating the gears 260 includes a hand crank 261 on a shaft journaled in the beam and carrying a gear 262 running in mesh with a gear 263 on a horizontal shaft 264. Worm gears 265 on the shaft run in mesh with the worm wheels 260. Rotation of the hand crank operates through the gearing just described to lift or lower the tank 254 and conveyor mechanism carried thereby. This permits adjustment of the chucks to correspond to the height of the bottles or other workpieces.

Referring to Fig. 9 the drive shaft 64 has mounted thereon a hub 266 to which are bolted upper and lower drive sprocket wheels 267 and 268 which drive the upper and lower sprocket chains 78 and 79. The hub is free for up and down adjustment on the shaft and is jour-

naled in ball bearings 269 and 270. The hub 266 is supported in the conveyor frame 271. A cap 272 covers the upper end of the shaft 64.

Upper spindles

Referring to Figs. 3c, 4 and 9, each spindle 253 comprises a vertical spindle shaft 275 connected through upper and lower bearing blocks 276 and 277 to the upper and lower chains 78 and 79. Pivot pins 280 connect the chains to the bearing blocks 276 and 277. The spindle is held vertical and guided during its travel by upper and lower rolls 281 and 282 running in grooves or tracks formed in upper and lower rails 283 and 284. The rails are bolted to the side walls of the tank 254. The curved portions of the tracks extending around the drive shaft 64 are formed (as shown in Fig. 9) in the upper and lower castings 285 and 286 which support the ball bearings for the driving sprocket wheels.

The rotative position and movement of each upper spindle in respect to its vertical axis are controlled substantially in the same manner as above described for the lower spindles. Such means as applied to the upper spindle includes horizontal arms 287 and 288 (Figs. 2 and 10) formed on the bearing members 276 and 277 and extending forwardly in their direction of travel. The arms carry at their forward ends, rolls running in upper and lower tracks 283, 284.

The weight of the spindles is supported on a track 290 formed in part by rails bolted to the side walls of the tank 254 and formed with grooves 291 in which run rolls 292 on arms 293 (Figs. 2 and 9) formed on the spindle shafts.

The spindle shafts 275 are all of the same construction. Each shaft is made hollow or formed with a bore extending throughout its length. Mounted in the upper half of each spindle is a tubular shaft 294 within which is a coil spring 295 held under compression between a stop block 296 in the upper end of the shaft 294 and a rod 297 mounted for vertical sliding movement in the lower end portion of the shaft 294. The rod 297 has a screw-threaded connection with a tubular plunger 298 extending downward through the lower part of the spindle and slidable up and down therein. The plunger 298 is square in cross section as shown in Fig. 10 to prevent rotation within the spindle and is formed with a bore 299 in the suction line.

The chuck 55 is connected to the plunger 298 through a cylindrical coupling member 300.

The chuck, as shown in Figs. 9 and 10A is formed with a tubular stem 301 extending upwardly within the coupling 300 and journaled in ball bearings therein, permitting free rotation of the chuck. The latter is provided with a ring gasket or liner 302 of rubber or other suitable material to make sealing contact between the chuck and the workpiece 50. The coupling 300 has a screw-threaded connection with a head 303 (Fig. 10A) formed on the lower end of the plunger 298.

Mounted within the head 303 is a valve 304 in the form of a tube slidable up and down within said head. The suction line extends from the mouth of the chuck 55 upwardly through the chuck stem, valve 304 and lateral openings 305 in the valve to the bore 299 extending upwardly through the plunger 298. A light coil spring 307 holds the valve 304 in its open position.

The shaft 294 carries at its upper end, a cam follower roll 310 which runs on a stationary cam track 311 during a portion of the travel of the spindle, thereby controlling the up and down movements of the shaft and its position within the spindle. A latch 312 pivoted to the spindle is adapted to hold the shaft 294 either in a lowered position as shown in Fig. 9 or in a lifted position when the latch is swung to the broken line position, Fig. 9. The latch engages a notch 316 in the shaft 294 for holding the shaft in either position. The latch carries a roll 313 which runs in a cam track 314 designed for holding the

latch in its neutral position (Fig. 4), and for swinging the latch into holding engagement with the shaft 294.

Bottle transfer to lower spindles

Referring to Fig. 2, when an upper spindle during its horizontal travel reaches the position 253a, it is directly over and in register with a bottle 50 on the carrying-in conveyor 51. At this time the latch 312 is holding the shaft 294 in a lifted position with the chuck 55 spaced a short distance above the mouth of the bottle. As the spindle advances beyond the position 253a a slight rise or hump 315 formed on the cam track 311 lifts the shaft 294 a short distance and thereby releases the latch 312. At the same time, the latch roll 313 enters the right-hand end of the track 314 and operates positively to swing the latch to neutral position. The spindle plunger is then gradually lowered as the roll 310 runs off the hump 315, thereby seating the chuck 55 on the bottle. Suction is then applied to the bottle as hereinafter described so that the bottle is held by the chuck. The cam track 311 is formed with a channel 311a for effecting a positive downward movement of the shaft 294 for seating the chuck on the bottle and then a continued downward movement of the shaft for a short distance after the chuck is seated, thereby operating through the coil spring 295 and plunger 298 to apply a sufficient holding pressure to the chuck to insure a good seal.

After suction is applied, the plunger with the bottle held thereon is lifted by the cam track 311, thereby lifting the bottle from the conveyor 51. The bottle while thus suspended, is carried forward to the position 50a at which it is directly over and in register with one of the lower spindles and during such forward movement is lowered so that the bottle is seated on the pad 54. The bottle then continues its travel while held between the pad and the chuck 55 until it reaches the printing zone.

Vacuum system

Air is exhausted from the vacuum chamber 255 through a suction pipe 318 (Fig. 2) and a pipe 319 depending from the beam 256 and extending through an opening in the upper wall of the tank 254 (Fig. 4). A casting 321 (Figs. 4 and 14A) provides a suction channel extending along the side wall of the tank and in communication with the vacuum chamber through a port opening 322. Each spindle shaft 275 is formed with an opening 323 extending through its inner wall opposite the channel 321.

A vacuum belt 324 (Figs. 2, 3c, 4) which may consist of an endless steel tape, is mounted to travel in a closed path which surrounds the tank 254 and in which the belt is interposed between the channel 321 and the spindles as the latter advance along said channel. The vacuum belt 324 is formed with openings 325 which register with the openings 323 in the spindle walls. The vacuum belt is driven at the same speed as the spindles by a pulley 326 (Fig. 2) which is mounted on the shaft 64' (Fig. 5) driven by the conveyor chains 78 and 79. The belt is trained over a driven pulley 327 (Fig. 3c), journaled on a stud shaft 328, carried by a cylindrical adjusting device or post 329 which serves as a tension and take-up device for the belt, and is mounted for rotative adjustment in the frame 254. The shaft 328 is eccentric to the post 329 so that rotation of the latter adjusts the pulley 327 for maintaining the desired tension in the vacuum belt. The post is held in its adjusted position by a clamping or locking device 329' (Fig. 2). Each of the pulleys 326 and 327 is provided with pins 330 spaced to agree with the spacing of the chuck spindles and arranged to engage the openings 325 in the vacuum belt for driving the latter.

The suction channel 321 as shown in Fig. 14A is formed in its outer wall with an elongated slot 321a, the forward end portion of which is tapered as shown in 321b for a purpose which will presently appear. The vacuum belt 324 overlies the opening 321a closing the

latter except at the ports 323 (Fig. 4) in the spindles and the registered openings in the vacuum belt.

As each spindle advances and is brought into register with the elongated opening 321a the suction applied through said opening exhausts the air through the suction line leading to the bottle which is attached to the spindle, thereby vacuumizing the bottle so that the chuck 55 holds the bottle during the transfer from the carrying-in conveyor 51 to the lower spindle. The tapered end portion 321b of the slot in the suction channel allows the air to be exhausted slowly from the bottle. If a bottle is missing so that an empty chuck 55 is connected into the suction line, the suction causes an upward draft of air through the chuck of sufficient force to lift the valve 304 (Fig. 10A) to closed position. The valve is then held closed by suction until the empty chuck passes beyond the slot in the suction channel 321. The end portion 321b of the channel being tapered, throttles the inflow of air and thereby serves to prevent an upward draft of air of sufficient force to close the valve while the bottle is being vacuumized.

Back-up roll mechanism

The back-up roll mechanism (shown in Figs. 1, 3b, 5, 14, and 23 to 28) will now be described. The upper and lower carrier chains 58 are driven by the shaft 60 which as shown in Figs. 5 and 3b is driven from the drum shaft 46 through a chain 330 trained over sprocket wheels secured to the shafts 46 and 60. Tension is maintained on the chain 330 by the take-up roll 330a adjustable in the frame 87.

The back-up roll mechanism is supported in a frame 331 in the form of a vertical hollow rectangular body with integral horizontal top and bottom extensions or plates 332 and 333. The back-up rolls 57 as heretofore described, are connected to the carrier chains 58 in an endless series. The rolls travel in a closed path surrounding the frame 331. Each roll 57 has associated therewith a mechanism for swinging the roll bodily outwardly as it enters the printing zone and holding it with a yielding pressure against the blanket, and means for retracting the roll as it leaves the printing zone. These individual roll assemblies are all alike and may be described as follows: the roll 57 consists of rubber or other soft resilient material which bears against the blanket and holds it with a yielding pressure against the workpiece during the printing operation, permitting the blanket to accommodate itself to irregularities in the surface to which the design is being applied.

The roll is mounted on a shaft 335 supported in arms 336 extending laterally from a cylindrical shell or casing 337 within which is a shaft 338. The shaft 338 has a fixed mounting in upper and lower frame members or carriers 339 and 340. The upper carrier 339 is guided during its travel by rolls 341 journaled thereon and running in a channel 342 or closed track in vertical register with the path of the carrier chains 58. The lower carrier 340 is guided in like manner by rolls 344 running in a lower track 345.

The roll 57 is swung bodily outward to bear against the blanket by a pair of torsion coil springs 346 mounted on the shaft 338. The lower coil spring is attached by a stud 349 (Fig. 27) to the shell 337 and at its upper end is attached to a pin 350 extending through the shaft 338. The upper spring 346 is anchored in like manner at its upper and lower ends to a stud 351 and the pin 350. Ball bearings 352 (Fig. 27) permit the shell 337 to rotate about the shaft 338 while the latter is held in fixed position within the carrier frames 339, 340.

A shaft 355 has a fixed mounting in the carrier frames 339, 340. Mounted on the shaft 355 is a coil spring 356 anchored at its upper end to the shaft by a pin 357 and at its lower end connected to a rocker 358 journaled to rock on the shaft 355. The rocker is formed with a laterally extending arm or lug 359 which extends into posi-

tion to engage the lower arm 336 in which the roll 57 is mounted and operates to swing the roll inwardly against the tension of the springs 346 after the printing operation, as presently described. The torsion spring 356 is of sufficient strength to swing the backing roll 57 inwardly against the opposing force of the springs 346. The upper and lower guide rolls 341 and 344 are in vertical alignment with the shafts 338 and 355. The carrier frames 339, 340 are connected to the chains 58 by means of pivot pins 360 in vertical alignment with the shafts 355.

The backing roll 57 is held in its retracted position, except while passing through the printing zone, by a latch 361 pivoted to the carrier frame 339 and formed with a hook to engage a keeper 362 attached to the arm 336. As the roll 57 enters the printing zone, the latch is released by a trip arm or cam 364 threaded on a screw shaft 365. Means for adjusting the trip arm includes a hand crank 366 (Fig. 23) connected to a shaft 367 which operates through gears 368, 369, shaft 370 and gear 371 attached to the screw shaft 365 for rotating the latter.

The rocker 358 is held in its inoperative position during the printing operation by a latch 372 or trigger which engages an arm 373 formed on the rocker 358. As the backing roll 57 leaves the printing zone a trip arm or cam 374 (Figs. 24 and 26) operates the trigger 372, thereby releasing the rocker 358 so that the torsion spring 356 rotates the rocker in the direction to swing the backing roll inwardly away from the blanket. The rocker is then rotated in the reverse direction, leaving the roll 57 re-set or re-engaged by the latch 361. The reverse movement of the rocker is caused by engagement of the arm 373 with the shaft 60 as the arm travels around said shaft. The rocker arm is thus swung outwardly allowing the roll 57 to move outwardly until the latch 361 re-engages its keeper thereby holding the roll retracted until it again reaches the printing zone.

The trip arm 374 is mounted on a screw-threaded shaft 375 and is adjusted in the same manner as the trip arm 364, the adjusting means including a hand crank 376 operatively connected to the trip arm through a shaft 377, gears 378, shaft 379 and gears 380.

The driven shaft 59 is adjustable for taking up slack in the carrier chains 58 and maintaining tension therein, by adjusting means comprising a ratchet wheel 381 keyed on a tubular shaft 382 in which the shaft 59 is journaled. Eccentric sleeves 383 attached to the shaft 382 bear against stop plates 384 on the frame 331. Rotation of the ratchet wheel 381 operates to rotate the sleeves 383 and thereby adjust the shaft 382 and the shaft 59 therein. A locking dog 385 holds the ratchet wheel in adjusted position.

Operation

Referring to Figs. 2 and 5 the operation may be summarized as follows:

The bottles 50 as they are carried forward on the carrying-in conveyor 51 are brought beneath and into register with the upper spindles carrying the suction chucks 55. Each chuck is lowered to engage a bottle, suction is then applied and the bottle lifted and carried forward into register with a lower spindle 77 and lowered to seat on the pad 54 or chuck carried by the lower spindle. The bottle while held by the chucks is advanced to the printing zone. As it passes through the printing zone, the blanket carrying the design to be transferred to the bottle is held against the bottle by a back-up roll 57. The blanket is traveling at a higher speed than the spindles so that the bottle rolls in contact with the blanket while the design is being transferred to the bottle. After leaving the printing zone the bottle is again vacuumized, lifted from the lower spindle and transferred to the take-out conveyor 82.

When a bottle on the conveyor 51 reaches the position indicated by the line 400 (Fig. 5) it is in register with an upper spindle 253 at the position 253^a (Fig.

2) with the chuck 55 spaced a short distance above the bottle. At this time the latch 312 (Fig. 9) is in the dotted line position and locking the chuck in its lifted position. As the bottle and the spindle move forward from position 400 to position 401 the hump 315 on cam track 311, lifts the chuck 55 a short distance sufficient to release the latch 312, allowing the chuck to move downward into sealing engagement with the bottle as the spindle advances beyond the hump 315. The spindle then travels along the suction channel 321 which extends from about the line 402 to 403 (Fig. 5) so that suction is applied and vacuumizes the bottle, thereby holding it to the chuck while the bottle is being transferred from the carrying-in conveyor to one of the lower spindles 77. The cam track 311 lifts the bottle off the conveyor 51 when the position 404 is reached so that the bottle is suspended from the upper spindle until brought over and into register with a lower spindle. The latch 312 remains in its neutral position while suction is maintained. About the time the spindle passes beyond the suction channel so that the suction is discontinued the latch 312 is moved into the locking position shown in full lines in Fig. 9, to hold the shaft 294 in a lowered position. This permits the chuck 55 to be held in engagement with the bottle neck by the downward pressure of the spring 295. This locking position of the latch is retained until position 407 is reached.

After the suction is discontinued and about the time or shortly after the latch 312 is operated to lock the shaft 294 down as just described, the register finger 233 (Figs. 12-14) is released by the cam 238 (at position 405) and is moved inwardly to operative position in the path of the stop lug 230 on the bottle. Also at this time the pad 54 with the bottle thereon is being rotated by means of the roll 213 (Fig. 11) running on the stationary track 214 and operating through the friction clutch or disk 219 to rotate the pad. The bell crank 222 is lowered by its cam 221 to break the toggle which it forms with the link 224 so that the expansion spring 210 maintains the friction drive through the clutch disk 219. The bottle is thus rotated until arrested by the stop finger 233 in its orientated position preparatory to having the printed design transferred thereto from the blanket 40. As the bottle reaches position 406, near the printing zone, the bell crank 222 (Fig. 11) is operated to lower the tube 211, thereby allowing the friction disk 219 to drop down and discontinue the friction drive. The register finger is also withdrawn at the same time, leaving the bottle free for rotation by the printing blanket 40 during the printing operation.

As the bottle enters the printing zone a backing roll 57 is swung outwardly and presses a blanket against the traveling bottle. The blanket is traveling at a higher speed than the bottle spindles so that the bottle is rolled along the surface of the blanket and thereby causes the design to be transferred from the blanket to the surface of the bottle. The backing rolls travel at the same speed as the bottles and maintain the pressure of the blanket against the bottles throughout the travel through the printing zone, while the blanket is traveling at a substantially higher speed. This relatively high speed of the blanket as compared with the bodily forward movement of the bottles, permits the printing to be effected while the bottles are traveling and extends the length of time provided for the printing of each bottle. In this connection it will be noted that the printing operation is continued for a greater length of time than that required for advancing the bottles the distance between the centers of adjacent bottles. The arrangement and operation are such that the speed differential between the blanket and the bottle is less than the speed of the blanket itself. This reduction in the relative velocity between the bottle and the blanket is found to be very important, particularly in high speed operation.

After a bottle has passed beyond the printing blankets, vacuum is again applied (as indicated schematically in

Fig. 5) for attaching the bottle to the suction chuck 55, the bottle is then lifted and while suspended, carried forward to the bottle take-out conveyor 82, lowered thereon and released. The mechanism for thus transferring the bottle to the take-out conveyor 82 is substantially similar to and operates in the same manner as that above described for transferring the bottles from the carrying-in conveyor to the spindles.

Any one or more of the inking units 30 may be used during a printing operation. The offset die rolls 32 are so spaced and arranged that a plurality of them may operate to transfer their respective designs to each of the blankets 40. The dies are so spaced that each blanket may transfer designs therefrom to diametrically opposite surfaces of a bottle. Where the apparatus is used for multiple color printing, the dies may apply the different colors in superposed relation to the blanket.

Modifications may be resorted to within the spirit and scope of our invention as defined in the appended claims.

We claim:

1. A printing machine comprising a die roll, a die thereon, means for inking the die, a blanket, means for driving the blanket in a path in which it is brought into contact with the die, means for rotating the die roll and transferring the design from the die to the blanket, means providing a hard, substantially unyielding surface in position to form a backing for the blanket during the transfer of the design to the blanket, means for mounting a workpiece with a round surface for rotation about its axis and holding it adjacent to the path of the blanket, a back-up roll mounted adjacent to the workpiece with the blanket interposed between the back-up roll and workpiece, means for holding the back-up roll against the blanket and thereby pressing the blanket against the workpiece, means for carrying the back-up roll and workpiece bodily forward at the same speed while the back-up roll is holding the blanket against the workpiece, the said speed of the back-up roll and workpiece being different from that of the blanket and thereby causing the workpiece and the back-up roll to roll along the blanket and cause the design to be transferred from the blanket to the workpiece while said pressure of the blanket against the workpiece is maintained, said back-up roll consisting of a soft resilient material by which the pressure on the blanket is distributed and the blanket caused to conform to any irregularities in the surface to which the design is being applied.

2. The machine as set forth in claim 1, the means providing said hard surface consisting of a drum, means for rotating the drum, and means for rotating the die roll at the same surface speed as that of the drum.

3. A printing machine comprising a drum mounted for rotation about a vertical axis, a plurality of die rolls mounted adjacent to the drum and spaced at intervals along the periphery of the drum, offset dies on the die rolls, means for inking the dies, a blanket mounted for travel in a path surrounding the drum with the blanket interposed between the drum and the die rolls, a carrier for rotatably supporting and carrying bottles or other workpieces in a path extending along a portion of the path of the blanket, mechanism for rotating the drum at a predetermined speed and driving the blanket at the peripheral speed of the drum, means for driving said carrier at a slower speed than that of the blanket and thereby carrying the workpieces through a printing zone extending along said portion of the path of the blanket, means for holding the blanket against the workpieces during their passage through the printing zone and thereby transferring the designs from the blanket to the workpieces, back-up mechanism comprising a back-up roll positioned on the opposite side of the blanket from the workpieces, and means for holding the back-up roll against the blanket directly opposite a workpiece and moving it forward through the printing zone with and at the same speed as the workpiece and thereby maintaining the blanket pressed against the workpiece during its passage through the printing zone.

4. The machine as defined in claim 3, said drum having a hard substantially unyielding surface forming a backing for the blanket while the design is being transferred thereto from the dies, said back-up roll consisting of a soft resilient material.

5. A printing machine comprising a blanket, means for printing designs thereon, means for advancing a series of articles in a predetermined path, said articles having round surfaces to receive the designs, means for causing the blanket with the designs thereon to traverse a printing zone through which the said articles are passing with the blanket in close proximity to the said articles and moving parallel with and relative to the articles during their passage through said zone, back-up roll mechanism including a back-up roll, means for pressing said roll against the blanket while the latter is traversing the printing zone with the back-up roll directly opposite a said article, and means for carrying the back-up roll forward through the printing zone at the same speed as the said article and maintaining the said pressure against the blanket while moving through the printing zone and thereby holding the blanket against said article and causing the design on the blanket to be transferred to the said article.

6. A printing mechanism comprising, in combination, a blanket, means for applying ink designs to the blanket, means for conveying the blanket in a predetermined path extending through a printing zone, means for advancing workpieces through the printing zone with the path of the workpieces in close proximity to and substantially parallel with the path of the blanket through said zone, and back-up roll mechanism including back-up roll units connected to form an endless chain, each said unit including a back-up roll and means for pressing the roll against the blanket and holding the blanket against a workpiece while traversing the printing zone.

7. A printing mechanism comprising a blanket, means for applying an ink design thereon, means for advancing the blanket in a path extending through a printing zone, back-up roll mechanism comprising a plurality of units connected to form an endless chain of said units, means for driving said chain in a closed path a portion of which extends parallel with and adjacent to a portion of the path of the blanket, each back-up roll unit comprising a back-up roll, rock arms in which the roll is mounted for rotation about its axis, spring means for rocking said arms and thereby moving the roll toward and into engagement with the blanket and holding said roll in engagement with the blanket while traversing the printing zone, and automatic means for retracting the back-up roll as it leaves the printing zone.

8. A printing mechanism comprising a blanket, means for applying an ink design thereon, means for advancing the blanket in a path extending through a printing zone, back-up roll mechanism comprising a plurality of units connected to form an endless chain of said units, means for driving said chain in a closed path a portion of which extends parallel with and adjacent to a portion of the path of the blanket, each said back-up roll unit including a back-up roll and a carrier in which the back-up roll is journaled for rotation about its axis, said carrier being mounted for rocking movement about an axis parallel with the axis of the back-up roll, a spring connected to said carrier and applying tension thereon in a direction to swing the back-up roll outwardly into engagement with the blanket and applying pressure to the blanket while the roll is traversing the printing zone, means for withdrawing the back-up roll as it leaves the printing zone, means for latching the roll in its withdrawn position, and means for releasing the latch as the roll again nears the printing zone.

9. The mechanism defined in claim 8, a latch carried by each said unit and movable into position to hold the roll in its retracted position, a trip device positioned to operate the latch and release the back-up roll as it enters the printing zone, and means for retracting the roll and

resetting the latch as the roll leaves the printing zone.

10. A printing machine comprising a blanket, means for applying ink designs thereto, means for driving the blanket and causing it to move in the direction of its length through a printing zone, means for moving workpieces through the printing zone, and back-up roll mechanism for holding the blanket against the workpieces while traversing the printing zone, said back-up roll mechanism including a plurality of units connected to form an endless chain, a framework in which the chain of units is mounted for continuous travel in a closed path, means for driving said chain of units, each unit including upper and lower frame members spaced apart vertically, a vertical shaft mounted in said members, rock arms mounted to rock about the axis of said shaft, a vertical back-up roll journaled in said arms, a torsion coil spring mounted on said shaft and connected to the shaft and one of said rock arms and operative to rock said arms and move the back-up roll outwardly and hold it against the blanket while traversing the printing zone, thereby pressing the blanket against the workpiece and causing transfer of the design to the workpiece.

11. The mechanism defined in claim 10, each said back-up roll unit including a latch mounted on one of said frame members, a keeper mounted on one of said rock arms in position to be engaged by the latch and thereby hold the back-up roll in a retracted position, automatic means for releasing the latch as the back-up roll enters the printing zone, and automatic means for retracting the back-up roll and resetting the latch as the roll leaves the printing zone.

12. The combination set forth in claim 11, the latch releasing means comprising a stationary cam mounted in the path of the latches, the resetting means comprising a second shaft mounted in said frame members, a second coil torsion spring mounted on said second shaft, a rocker arm journaled on said second shaft and extending into the path of one of said rock arms in which the back-up roll is mounted, said second torsion spring being connected at its ends respectively to the said second shaft and to the rocker arm journaled thereon and applying pressure to the roll carrying rock arm in a direction to swing the roll inwardly to a retracted position, means including a second latch for holding the rocker in a retracted position and thereby permitting the operation of the back-up roll, means for releasing said second latch as the back-up roll leaves the printing zone and thereby permitting said second spring to operate said rocker in a direction to retract the said roll, and means for then reversing said rocker and resetting both said latches.

13. A printing machine comprising blankets connected end to end to form an endless series, a blanket drum around which the series of blankets is extended, a drum shaft on which the drum is mounted, sprocket chains, means for connecting the blankets to said chains, sprocket wheels on the drum shaft and in driving engagement with said chains, means for rotating the drum shaft and thereby rotating the drum and driving the blankets, die rolls mounted for rotation, dies carried by said rolls, means for holding the die rolls in position for the dies to make rolling contact with the blanket, means for inking the dies and causing the designs to be transferred to the blankets, said drum running in contact with the blankets and forming a backing for the blankets while the designs are being transferred thereto, the means for connecting the blankets to said chains including clamping bars gripping the end edges of the blankets, each clamping bar at the forward end of a blanket being pivotally connected to the chains and the clamping bar at the other end of the blanket having a spring connection with the chains by which the blanket is held under tension.

14. Printing apparatus comprising a blanket, a carrier for the blanket including parallel chains, means connecting the blanket to said chains including clamping bars extending along the end margins of the blanket and

clamped thereto and means connecting one of said bars to the chains and forming a positive driving connection between the chains and the said bar, means providing a spring tension and take-up connection between the 5 chains and the other said clamping bar.

15. Printing apparatus comprising a blanket, a carrier for the blanket including parallel chains, means connecting the blanket to said chains including clamping bars extending along the end margins of the blanket and 10 clamped thereto and means connecting one of said bars to the chains and forming a positive driving connection between the chains and the said bar, means providing a spring tension and take-up connection between the chains and the other said clamping bar, said tension and take-up 15 means including telescoping members connected respectively to the clamping bar and chains, and a coiled compression spring held under compression between the said telescoping members and thereby applying tension to the blanket.

20. 16. A machine for printing lettering or other designs on the cylindrical surface of a workpiece, said machine comprising a drum having a hard, substantially unyielding cylindrical surface, a blanket mounted to travel in a closed path in which the blanket passes around the drum in contact with said hard surface, means for rotating the drum about its axis and driving the blanket in said path, a die roll, a die thereon having the design which is to be printed on said workpiece, means for inking the die, means for rotating the die roll with the die bearing lightly 25 on the traveling blanket and with the drum directly opposite the die roll and forming a backing for the blanket, whereby the design is transferred to the traveling blanket, means for mounting the workpiece for rotation about its axis with the said surface of the workpiece closely adjacent to the path of the blanket, a backing roll positioned directly opposite and adjacent to the workpiece with the blanket interposed between the backing roll and workpiece, means for pressing the backing roll against the blanket and thereby holding the blanket against the workpiece, means for moving the backing roll and workpiece 30 bodily forward at the same speed through a printing zone while the backing roll is opposite the workpiece and pressed against the blanket, the said speed of the backing roll and workpiece being slower than that of the blanket, and thereby causing the workpiece to roll in contact with the blanket and transfer the design to the workpiece, said backing roll consisting of soft resilient material whereby the blanket with the design thereon is caused to adapt itself to any irregularities in the surface to which the design is being applied.

50. 17. The machine defined in claim 16, the said backing roll being of much smaller diameter than that of the workpiece.

55. 18. Apparatus for printing designs on the cylindrical surface of a workpiece, said apparatus comprising a drum having a hard, substantially unyielding cylindrical surface, a blanket trained over the drum, means for applying an ink design to the blanket, means for rotating the drum and driving the blanket, means cooperating with the drum for guiding the blanket in a closed path, a carrier in which the workpiece is mounted for free rotation about its axis, means for moving the carrier and the workpiece therein in a path adjacent to and substantially parallel with a portion of said path of the blanket and at a different speed from that of the blanket, a backing roll, means for advancing the backing roll at the same speed as the workpiece in a path extending along and adjacent to said portion of the path of the blanket and with the blanket interposed 60 between the workpiece and backing roll and with the backing roll and workpiece directly opposite each other and advancing at the same rate along said portion of the path, and means to apply a yielding pressure to the backing roll and causing it to hold the blanket against 65 the workpiece while traversing said portion of the path.

70. 75.

of the blanket and thereby causing a transfer of the design from the blanket of the workpiece.

19. The apparatus defined in claim 18, the means for applying the design to the blanket comprising a die roll and an offset die thereon having said design and means for positively rotating the die roll at the same surface speed as that of the drum and with the die bearing lightly against the blanket for transferring the design thereto.

20. The combination of a drum, a blanket trained over the drum, means for rotating the drum and driving the blanket, means cooperating with the drum for guiding the blanket in a closed path extending through a printing zone, means for mounting and supporting a workpiece having a cylindrical surface for rotation about the axis of said surface, means for driving the workpiece support and carrying the workpiece through the printing zone at a slower speed than that of the blanket, a backing roll adjacent to and directly opposite the workpiece with the blanket interposed between the workpiece and backing roll, inking means for applying a design to the blanket, means for pressing the backing roll against the blanket and thereby holding the blanket in contact with the cylindrical surface of the workpiece, and means for driving the backing roll through the printing zone while holding the blanket against the workpiece and with the backing roll and workpiece advancing at the same speed, and thereby causing the design to be transferred to the workpiece while passing through the printing zone, the backing roll consisting of soft resilient material.

21. A printing machine comprising a drum mounted for rotation about a vertical axis, a plurality of die rolls mounted adjacent to the drum and spaced at intervals along the periphery of the drum, offset dies on the die rolls, means for inking the dies, a blanket mounted for travel in a path surrounding the drum with the blanket interposed between the drum and the die rolls, a carrier for rotatably supporting and carrying bottles or other workpieces in a path extending along a portion of the path of the blanket, mechanism for rotating the drum at a predetermined speed and driving the blanket at the peripheral speed of the drum, means for driving said carrier at a slower speed than that of the blanket and thereby carrying the workpieces through a printing zone extending along said portion of the path of the blanket, means for holding the blanket against the workpieces during their passage through the printing zone and thereby transferring the designs from the blanket to the workpieces, back-up mechanism including back-up roll units, means for driving said units in a closed path extending along the path of the blanket, with the back-up roll units on the inner side of the blanket, each said back-up roll unit including a back-up roll and means for moving the roll outwardly against the blanket and applying a yielding pressure which is transmitted through the blanket to the workpiece, and means for driving the back-up roll units and causing them to advance at the same speed as that of the workpieces and with the back-up rolls directly opposite the workpieces during their travel through the printing zone.

22. A printing machine comprising a blanket, means for printing designs thereon, means for advancing a series of articles in a predetermined path, said articles having round surfaces to receive the designs, means for causing the blanket with the designs thereon to traverse a printing zone through which the said articles are pass-

ing with the blanket in close proximity to the said articles and moving parallel with and relative to the articles during their passage through said zone, back-up roll mechanism comprising a plurality of back-up roll units connected to form an endless chain, means for driving said chain in a closed path extending along the printing zone and carrying said units through the printing zone at a slower speed than that of the blanket, each said unit comprising a back-up roll and means for moving the roll outwardly against the blanket and applying pressure through the blanket to a said article and thereby causing the design to be transferred from the blanket to said article.

23. A machine for printing lettering or other designs on the cylindrical surface of a workpiece, said machine comprising a drum having a hard, substantially unyielding cylindrical surface, a blanket mounted to travel in a closed path in which the blanket passes around the drum in contact with said hard surface, means for rotating the drum about its axis and driving the blanket in said path, a die roll, a die thereon having the design which is to be printed on said workpiece, means for inking the die, means for rotating the die roll with the die bearing lightly on the travelling blanket and with the drum directly opposite the die roll and forming a backing for the blanket, whereby the design is transferred to the travelling blanket, means for mounting the workpiece for rotation about its axis with the said surface of the workpiece closely adjacent to the path of the blanket, a backing roll positioned directly opposite and adjacent to the workpiece with the blanket interposed between the backing roll and workpiece, means for pressing the backing roll against the blanket and thereby holding the blanket against the workpiece and causing the workpiece to roll in contact with the blanket and transfer the design to the workpiece, said backing roll consisting of soft resilient material whereby the blanket with the design thereon is caused to adapt itself to any irregularities in the surface to which the design is being applied, the path of the blanket including a straight-line portion extending along a printing zone, means for advancing the workpiece and backing roll bodily with the blanket along said straight-line portion of the blanket path at the same speed and with the blanket held against the workpiece while traversing the printing zone and with the workpiece and backing roll traveling at a slower speed than the blanket.
